GOLF BALL

Hiram N. Huse, Providence, R. I., assignor to
United States Rubber Company, New York,
N. Y., a corporation of New Jersey

Application August 16, 1941, Serial No. 407,134

5 Claims. (Cl. 273—62)

This invention relates to golf balls, and more particularly to improvements in the construction of the ball body.

In manufacturing golf balls, it is the usual practice to provide a center formed of yielding material such as a rubber core or a confined fluid, about which a rubber tape or thread is wound to form the ball body, and this ball body is provided with a protecting cover of balata.

In the cheaper golf balls the ball body is commonly formed from start to finish of a narrow rubber tape or thread wrapped helically about the core until the ball body has reached the full size to which the cover is to be applied. In the more expensive, high-tension, balls it is now the usual practice to wind a wide rubber tape helically about the core until the ball body is nearly large enough to receive the cover, and then transfer the ball body to another machine where a narrow tape or thread is wound upon the ball body until it is large enough to receive the cover. Both the wide and narrow tape are wound under high tension to give the ball high density.

A wide tape is used to form the greater portion of the ball body of a high tension ball because it eliminates to a large degree the voids which occur between the adjacent helical windings, over those which occur when a narrow tape or thread is used, and forms a denser ball. The golf ball manufacturers would prefer to wind the entire ball body from start to finish of wide rubber tape, but the difficulty is that if the exterior of the ball body is formed of wide tape the surface of the ball body will be so smooth that it will not afford a good anchorage for the balata cover. Therefore it is now the general practice in making high density balls to form the major portion of the ball body of wide rubber tape, but the outer periphery thereof of narrow rubber tape or thread which will cause a sufficient number of voids to be formed between the adjacent coils to give the cover good anchorage upon the ball body.

This practice of producing the ball body partly of wide tape and partly of narrow tape or thread is open to several objections. One is that it necessitates the transfer of the ball body from one winding machine to another to complete the winding operation, which is more expensive than winding the entire ball on a single machine. Another is that in the high tension ball, every effort is made to form the numerous helical windings under high tension, and a loss of tension occurs at the point where the transfer is

made from a wide to a narrow tape. Another is that an abrupt change necessarily occurs at the point where the wide tape terminates and the narrow tape begins so that the ball body is practically free of voids up to this point and is formed with substantial voids from this point outwardly, where as a gradual increase in the size of these voids toward the cover is deemed desirable.

Having in mind the foregoing one important feature of the present invention resides in a golf ball, the ball body of which is formed of a wide tape throughout a major portion thereof and a narrow tape or thread adjacent the outer periphery of the ball body but both are formed in one continuous and non-interrupted winding operation that avoids the necessity of transferring the ball from one machine to another.

Another important feature resides in a ball the ball body of which is so constructed that the change over from the wide tape forming the helical winding for the major portion of the ball body, to the narrow tape forming the outer periphery of the finished ball body is gradual throughout a number of convolutions. As a result of this construction there is no abrupt transfer from a wide to a narrow tape, and no loss of tension such as occurred heretofore when the transfer took place, and the voids increase gradually in size as the ball body approaches its final size.

This novel and highly desirable construction is secured by employing a wide rubber tape to form the entire ball body, and by gradually reducing the width of the tape near the outer periphery of the ball body by twisting the tape about its longitudinal axis as it is wound on the ball and thereby reduce its width near the ball cover. This twisting of the tape to reduce its width and the extent to which its width is reduced can be readily controlled by regulating the amount of twist imparted to the tape as it is delivered to the ball.

It is herein contemplated that when the ball body has been built up to the desired size with the helical windings of the wide tape in a flat condition, then the width of the tape is gradually reduced by twisting the tape, and the amount of twist imparted to the tape per unit length is preferably increased outwardly until the ball body reaches full size.

If a substantial amount of twist is imparted to the tape its width will be reduced to such an extent that it will lie on the ball in the form of a narrowed tape or thread, to thereby form a ball body which is sufficiently rough at its outer

periphery and has sufficient voids to cause the cover to be firmly anchored thereupon.

This highly desirable construction whereby the entire ball body may be formed of one continuous rubber tape which lies about the core in a flat condition throughout a major portion of the body and in a twisted and folded condition of greatly reduced width at the outer periphery of the ball body, is readily secured by providing any one of a number of well known types of ball winding machines with an attachment which will serve to rotate the source of tape supply and twist the tape as it is delivered to the winding position.

The above and other features of the present invention will be more fully understood from the following description when read in connection with the accompanying drawings in which:

Fig. 1 is a vertical transverse sectional view through a golf ball winding machine adapted to wind a ball in accordance with the present invention, the view being taken adjacent the winding position.

Fig. 2 is a longitudinal sectional view through the upper portion of the machine shown in Fig. 1.

Fig. 3 is a more or less diagrammatic view showing part of the tape as it lies on the ball body in a wide, flat condition, and part in a folded condition near the outer periphery of the ball body; and

Fig. 4 is a view of a golf ball constructed in accordance with the present invention, shown partly in section and also with a part of the cover removed.

The golf ball winding operation herein contemplated may be carried out on any one of a number of well known types of winding machines, since the twist which is to be given the rubber tape lying near the outer periphery of the ball may be imparted thereto upon a separate and independent machine before starting the present winding operation, or this tape may be twisted as it is being delivered to the winding position. It is deemed preferable, however, to provide the ball winding machine with an attachment for imparting the desired twist to the tape as it is advanced towards the golf ball winding position.

One good practical type of ball winding machine which may be used in carrying out the present invention is shown, described and claimed in the Cobb Patent No. 1,270,009. The machine herein shown is for the most part similar in construction and operation to that disclosed in said patent, but has associated therewith mechanism for imparting the desired twist to the rubber tape as it is advanced to the ball winding position.

In the machine shown in the drawings the operating parts are supported by a main casing having the front wall 10, rear wall 11, end walls 12 and top 13. Mounted upon this top 13 are the spaced frames or housings 14. These housings are spaced from each other sufficiently to provide a clearance space between them in which the ball winding heads 15 and 16 may rotate. These heads are supported for sliding movement towards and from each other by the relatively long sleeves 17 and 18 which are slidably mounted in the housings 14, and are prevented from rotating by the keys 19. Each head is secured to a long hollow shaft 20 journaled in a non-rotating sleeve 17 or 18, and each of the shafts 20 is provided at its outer end with a driving gear 21 which serves to rotate the head. Each shaft 20 has rotatably mounted therein a shaft 22 that is driven by a gear 23, and the function of this

shaft is to turn the ball supporting disks 24 rotatably mounted in each head. The gears 21 and 23 mesh with and are driven by the gears 25 and 26, one of which is slightly larger than the other as shown, and these gears are secured to and are driven by the main drive shaft 27 which is rotatably supported at 28 and may be driven by the belt pulley 29.

The non-rotating sleeves 17 and 18 are continuously urged towards each other to thereby hold the heads 15 and 16 in yielding engagement with the ball B to support and rotate the same. To this end the sleeve 17 has connected thereto the vertically disposed arms 30 which are rigidly secured to and extend upwardly from the horizontal rocking shaft 31, which shaft is journaled in bearings 32 mounted upon the top 13. The arms 30 are bifurcated at their upper ends to receive the cooperating pins 33 projecting laterally from the opposite walls of the sleeve 17. The shaft 31 has rigidly secured thereto to extend horizontally therefrom the arm 34, the outer end of which is provided with the gear segment 35. The other non-rotating sleeve 18 is similarly equipped with the upright arms 36 and horizontal arm 37 which are rigidly secured to the rocking shaft 38 supported by the brackets 39. The arm 37 is provided at its outer end with the gear segment 40.

The construction is such that the cooperating gear segments 35 and 40 cause the arms 34 and 37 to move together as the heads 15 and 16 are moved towards or from each other, and these heads are continuously urged towards the ball engaging position by the weight 41 which is suspended from the gear sections 35 and 40 by the links 42. When it is desired to separate the heads to release the ball B this may be done by engaging the upstanding lever 43, disposed at the rear of the machine, with the hand and push it rearwardly to thereby force the heads apart. This lever is pivotally supported from the machine frame by the shaft 44 and is provided with a frontwardly extending finger 45 that is adapted to engage the lower face of the gear segment 40 to lift the same when the lever 43 is pushed rearwardly, and thereby operate the upstanding arms 39, 36 to force the heads apart.

The mechanism so far described by reference numerals forms no essential part of the present invention and operates in substantially the same manner as the similar construction disclosed in the above cited Cobb patent. Each head 15 and 16 has associated therewith a ball engaging roller 46 adapted to cooperate with the adjacent disks 24 to hold the ball between the heads for rotation upon the longitudinal axis of the shafts 22 and also relative to such axis.

The rubber tape T to be wound on the ball B is supplied to the ball under tension from a position in front of the winding machine. Various means might be provided for tensioning this tape as it is delivered to the ball, and the means shown consists of an upper tape receiving drum 47 and a lower tape receiving drum 48. These drums are rotatably supported in spaced relation to each other by the bracket 49 secured to the machine frame. The upper drum has associated therewith a brake strap anchored at one end and having an adjusting thumb nut 50 at its other end as shown, and the lower brake drum has a similar strap anchored at one end and provided at its other end with the adjusting thumb nut 51. The arrangement is such that as the tape T is unwound from its source of supply, such as the spool 52, it passes upwardly to the drum

48 about which it may be looped to tension the tape, and is then looped around the drum 47 to further tension it. The tape is then lead to the ball winding position.

The present invention contemplates, as above pointed out, that after the ball body has had sufficient tape T wound tightly thereupon in a flat condition to bring the ball up to a predetermined size, then the rest of the tape is to be twisted or folded as it is supplied to the ball to complete the winding operation. The present invention further contemplates that the twist imparted to the tape be slight at first and increased progressively as the ball winding operation approaches completion.

One good practical form of mechanism which is adapted to cooperate with the ball winding machine illustrated will now be described, and such mechanism is designed to supply the tape to the winding position in an untwisted condition until the ball body has reached a predetermined size, and then twist the tape a gradually increasing amount as the ball body approaches its full size.

The tape supply spool 52 is supported between the upstanding brackets 53 to rotate upon its horizontal axis 54. The brackets 53 are rigidly secured to the rotating turn table 55 which is rotatably supported by the vertical shaft 56 journaled in a bracket 57 that forms part of the casting 58 secured to the machine casing. The shaft 56 is slidably mounted in the bracket 57 so that the table 55 may be raised and lowered. The arrangement is such that this table may be lowered into engagement with a driving disk 59 secured to one end of the shaft 60. This shaft is journaled in the casing 58 for rotating and longitudinal sliding movement. The arrangement is such that the speed at which the table 55 is rotated may be varied by sliding the driving shaft 60 to move its disk 59 towards and from the axis of the table 55.

The shaft 60 is driven from the main drive shaft 27 by the cooperating upper bevel gears 61 that drive the vertical shaft 62, and this shaft in turn through the cooperating lower bevel gears 63 drive the shaft 60. The bevel gear 63 upon the shaft 60 is slidably mounted thereupon and is drivingly connected to this shaft by the key 64.

The present invention contemplates mechanism whereby the driving disk 59 will be automatically advanced towards the axis of the table 55, as the size of the ball B approaches its final size. To this end the rocking shaft 31 has rigidly secured thereto the laterally projecting arm 65. The outer end of this arm is connected by a rod 66 to the outer end of the horizontally extending arm 67 forming part of a bell-crank lever 68 that is pivotally mounted at 69 upon a fixed bracket 70. The upper end of this bell-crank lever is provided with a sleeve 71 journaled upon the shaft 60. The arrangement is such that as the heads 15 and 16 are forced apart by the increased size of the ball, the outer end of the arm 65 will be elevated and this will rock the bell-crank lever 68 to thereby slide the shaft 60 in a direction to move the driving disk 59 towards the center of the table to increase its speed. The result of this is to increase the number of twists per unit length imparted to the tape T as the ball B grows in size.

It is desirable that the tape twisting mechanism just described shall remain inactive throughout the early winding stages and until the major portion of the tape T has been wound upon the

ball body. To accomplish this, in the construction shown, the central shaft 56 for the table 55 has an end that extends downwardly below the bearing bracket 57 so that this end may rest upon an end portion of a rocking lever 72, the opposite end of which is pivotally mounted at 73. The arrangement is such that if this lever 72 is raised it will lift the table 55 out of engagement with its driving disk 59. Means is provided for normally supporting this lever 72 in its elevated position to hold the table 55 out of engagement with the rotating disk 59 so that the table will not be driven by this disk, and also will not interfere with the longitudinal sliding movement of the shaft 60 at this time by the dragging of the disk 59 against the table 55. The lever 72 is conveniently held in the raised position just mentioned by a connecting rod 74 the upper end of which is secured to one arm of a rocking lever 75 which is pivotally mounted at 76 upon a bracket 77 secured to the main casing.

The lever 72 is shown in Fig. 1 of the drawings in its lowered position with the table 55 resting upon the disk 59 to be driven thereby. This is the position these parts occupy when the lever 75 is in the full line position in which it is shown in Fig. 1. When, however, the lever 75 is rocked to its dotted line position of Fig. 1 and is retained in this position by the latch 78 which is pivotally supported at 79, the lever 72 will be sufficiently elevated to hold the table 55 out of engagement with the disk 59.

It is desirable to provide means for automatically initiating rotation of the table 55 to start twisting the tape T when the ball B has reached a predetermined size. This is accomplished in the construction shown by providing the latch 78 with a spring 80 which normally holds this latch in its dotted line position of Fig. 1, that is the position in which the table 55 is out of engagement with its disk 59, and by providing this latch with an upwardly projecting end 81 which is connected to a sliding core within the solenoid 82. The arrangement is such that when this solenoid is excited it will retract its core to thereby rock the latch 78 to its full line position to unlatch the lever 75 and allow the table to move downward into engagement with the rotating disk 59. The solenoid 82 is connected by conductors, not shown, to a switch having the extension 83 and mounted in a casing 84 secured to the machine casing. This extension is adapted to be engaged by a screw 85 which may be adjustably mounted upon the sliding sleeve 18 as shown in Fig. 2. The arrangement is such that when the ball B is large enough to cause the screw 85 to engage the extension 83 the circuit will be closed to operate the solenoid and release the latch 78. This circuit should be under the control of the latch 78 so that it can be closed only when the latch is in its dotted position of Fig. 1.

Since it is desired that the table 55 be held out of engagement with the driving disk 59 during the greater portion of the winding operation, the hand operated lever 43 is provided at its lower end with the laterally extending finger 86 having an adjustable bolt 87 adapted to engage the lever 75 when the lever 43 is moved rearwardly, to thereby rock this lever 75 to its dotted line position to be held in this position by the latch 78. This construction insures that the table 55 will be raised when the lever 43 is in its rearward position.

The winding machine illustrated in Figs. 1 and 2 of the drawings operates as follows: The golf ball center or core is placed by hand between the cooperating heads 15 and 16 and the power is

turned on to rotate the heads and wind the tape T upon the core. This operation is continued until the ball body reaches the approximate size indicated by the juncture of the parts T and T' in Fig. 4. At this point the electric circuit will be closed by the screw 85 engaging the extension 83, to thereby trip the latch 78 and permit the table 55 to engage the rotating disk 59 to be driven thereby and slowly rotate the spool 52 to twist the tape T. As the ball body increases in size the driving disk 59 will be moved inwardly toward the axis of the table 55 to thereby increase the table speed and impart a higher twist to the tape T so as to gradually decrease the width of this tape as the ball increases in size as indicated in Fig. 3.

It will be understood from the foregoing that as a result of the present invention the entire ball body may be wound on a single machine in one continuous operation and from one continuous length of rubber tape, and that the major portion of the ball body may be wound of a wide tape to secure a high degree of compactness and as the full size of the ball body is approached the tape is twisted and folded to reduce its width so that it will resemble a narrow tape or thread as it lies on the ball body at the outer periphery thereof to provide the desired firm anchorage for the balata cover.

Fig. 4 of the drawings shows a golf ball constructed in accordance with the present invention, and which consists of a center or core C of any well known or preferred construction, and about which the wide rubber tape T is tightly wound until the ball body approaches full size. From this point outwardly the ball body is formed of the same tape but the tape is twisted or folded to produce the narrow tape or thread indicated by T', and to which the cover X may be firmly anchored.

It will be apparent from the foregoing that the size and shape of the voids near the outer periphery of the ball body may be controlled at will by controlling the amount of fold or twist that is imparted to the tape as it is supplied to the ball body. This makes it possible to provide a ball body, the outer periphery of which will serve best to anchor the cover thereto. By gradually increasing the twist of the tape as the ball body increases in size, as herein contemplated, voids that are somewhat conical in shape may be produced, which will afford the cover better anchorage than the voids produced heretofore, by using the same size narrow thread to form the entire

portion of the ball body near its outer periphery.

Having thus described my invention, what I claim and desire by Letters Patent is:

1. A golf ball having a ball body formed of successive convolutions of a single elastic tape the width of which greatly exceeds its thickness, and having this tape wound in a flat condition throughout a large portion of said body and in a twisted and folded condition of greatly reduced width and increased thickness at the periphery of the ball body, the change from the wide to the narrow condition of the tape being gradual throughout a number of convolutions.
2. A golf ball having a ball body the outer periphery of which is formed of windings of a narrow elastic tape and the interior of the body nearer the center is formed of windings of a wide elastic tape the width of which greatly exceeds its thickness, and wherein the narrow tape is formed of the wide tape by twisting and folding the latter to greatly reduce its width and increase its thickness.
3. A golf ball having a ball body the outer periphery of which is formed of windings of a narrow elastic tape and the interior of the body nearer the center is formed of windings of a wide elastic tape the width of which greatly exceeds its thickness, and wherein the narrow tape is integral with the wide tape and is formed from the latter by twisting and folding the wide tape to greatly reduce its width and increase its thickness.
4. A golf ball wherein at least a substantial portion of the body thereof is provided with successive convolutions of a long length of unbroken elastic tape the width of which greatly exceeds its thickness, and wherein the tape is wound at the outer periphery of the body in a twisted and folded condition of greatly reduced width and increased thickness and is wound nearer the ball center in a flat and much wider condition, the change in the width of the tape inwardly from said outer periphery being very gradual.
5. A golf ball wherein at least a substantial portion of the body thereof is formed of successive convolutions of one continuous and unbroken elastic tape the width of which greatly exceeds its thickness, and wherein the tape is wound at the outer periphery of the body in a twisted and folded condition of greatly reduced width and increased thickness and is wound nearer the ball center in a flat and much wider condition.

HIRAM N. HUSE.
